UNITED STATES PATENT OFFICE.

WILLIAM M. HARRISON, OF NEW YORK, N. Y., ASSIGNOR, BY MESNE ASSIGNMENTS, TO THE ECLIPSE CHEMICAL COMPANY, OF SAME PLACE.

DESIGN FOR A CYLINDER FOR HAND FIRE-EXTINGUISHERS.

SPECIFICATION forming part of Design No. 24,587, dated August 20, 1895.

Application filed June 19, 1895. Serial No. 553,366. Term of patent 14 years.

To all whom it may concern:

Be it known that I, WILLIAM M. HARRISON, a citizen of the United States, residing in the city, county, and State of New York, have invented and produced a new and original Design for Cylinders of Hand Fire-Extinguishers, of which the following is a specification, reference being had to the accompanying drawing, forming a part thereof, which shows 5 a cylinder for a hand fire-extinguisher designed according to my invention.

The design consists of an elongated cylinder having near each end an encircling band, whose ends are formed into a conventional 10 bow-knot. At the base of the cylinder its walls are slightly contracted, and at the top they flare or slightly expand, and the top or cap of the cylinder is convex and presents to the eye a somewhat flattened curve. About 15 midway between the two bow-knots are diminutive representations of two of the cylinders, one being represented as grasped in the left hand, while the right hand is shown as manipulating the device that closes the outlet for the discharge of the fire-extinguishing liquid; while the other is shown as grasped in

the left hand and the fire-extinguishing fluid as emerging therefrom in a spray or diffused stream. So far as the question of color is concerned, I prefer that the cylinder proper 30 shall be buff and the bands and bow-knots and diminutive representations of the cylinders of light blue.

The essential feature of this design is the holder for the fire-extinguishing fluid, the 35 same being cylindrical in form and having the encircling band and bow-knot near each end thereof, together with the diminutive representations of two of the cylinders, as above described, located between the two 40 bow-knots.

I claim—

The design for a cylinder for hand fire-extinguishers, substantially as herein shown and described.

Witness my hand this 18th day of June, 1895.

WILLIAM M. HARRISON.
